CLAIM

We claim the ornamental design for a current sensor, as shown and described.

DESCRIPTION

FIG. 1 is a front perspective view of a current sensor.
FIG. 2 is a front elevation view of the current sensor;
FIG. 3 is a rear elevation view of the current sensor;
FIG. 4 is a left side view of the current sensor;
FIG. 5 is a right side view of the current sensor;
FIG. 6 is a top plan view of the current sensor; and,
FIG. 7 is a bottom plan view of the current sensor.
